CARL F. FRAUENBERGER, OF HARTFORD, CONNECTICUT, ASSIGNOR, BY MESNE ASSIGNMENTS, TO S. H. ROSENBERG, OF BROOKLYN, NEW YORK.

SHEET-FEEDING MECHANISM.

Application filed October 31, 1924. Serial No. 747,028.

This invention relates to improvements in sheet feeding mechanism and, while the improvements are capable of other applications, they are particularly designed for use 5 with a cutting and creasing press.

A press of this type customarily has a substantially vertical bed with which a swinging platen cooperates and the face of the platen, when in sheet receiving position, lies 10 at an angle to the horizontal. Prior feeders for this type of machine have operated to push the top sheet of a vertical stack from a magazine over the adjacent and highest edge of the platen and to slide it in place 15 against the usual stops mounted adjacent the opposite and lowest edge of the platen. While this scheme solves, in one way, the problem of feeding a sheet from a vertical stack into an adjacent non-parallel and 20 downwardly inclined platen, the solution is not ideal because whenever the forward and leading edge of the sheet meets the least obstruction it catches and, being pushed from the rear edge, becomes crumpled, creased or 25 broken. When it is attempted to pull the sheet by gripping its forward edge, the usual nipper mechanisms do not operate satisfactorily because they travel in a straight line 30 parallel with the top of the stack and, when the nippers release the forward edge of the sheet, such edge, due to the inclination of the platen, is at best a considerable distance 35 above the lower edge of the platen. Consequently, when the sheet is released it has to drop a considerable distance in order to 40 reach the platen and the sheet is very likely to become improperly positioned. While some range of free fall for the sheet is usually permitted, such range needs to be 45 kept as short as possible because the movement of the sheet is not then positively controlled.

The main object of this invention is to 45 provide a sheet feeding mechanism for the purpose described which includes nipper mechanism to pull the sheet from the magazine to a position over the platen, characterized in that the nippers move at first outwardly parallel with the face of the stack of

50 sheets in the magazine and then swing downwardly until they become approximately parallel with the sheet receiving face of the platen and lie closely adjacent thereto at the time when the sheet is released to drop upon 55 said face.

Other objects and advantages will appear in the following description and in the illustrative embodiment of the invention in the accompanying drawings, in which:—

Fig. 1 is a side elevational view showing 60 the cutting and creasing press in associated relation with the sheet feeding mechanism of this invention;

Fig. 2 is a similar but fragmentary view, 65 showing the parts, as positioned at the end of the sheet feeding movement;

Fig. 3 is an enlarged fragmentary side elevational view, with parts broken away, of the sheet feeding mechanism alone;

Figs. 4 and 5 are sectional elevational 70 views taken on the lines 4—4 and 5—5 of Fig. 6;

Fig. 6 is a top plan view of the sheet feeding mechanism;

Fig. 7 is a fragmentary sectional elevational view of the rear portion of the magazine; and

Fig. 8 is a view somewhat similar to Fig. 3 but showing the parts as positioned during 75 the approach of the nippers to the magazine; and

Referring to these drawings; the invention is disclosed, by way of illustrative example, 80 in connection with a cutting and creasing press. Machines of this type are used generally in the art of making cardboard boxes and the like and are too well known to require detailed description and illustration herein. For the present purposes, it will suffice to state that the press comprises a 85

frame A on which is formed a substantially vertical bed b, and a platen c which cooperates with the bed and is movable from the position shown in Fig. 1 to the sheet receiving position shown in Fig. 2. The platen c 90 is provided with studs d one on each side thereof and these studs are connected by links e to crank pins f carried by gears g.

Gears *g* are fixed to a shaft *h*, one near each end thereof, and are driven from pinions *i*, fixed on the main drive shaft *j* of the press.

The mechanism for feeding sheets successively to platen *c* is mounted upon a skeleton frame *B* which also functions as a magazine and receives a vertically movable platform *10* upon which the sheets *s* are carried in vertically stacked relation. Associated with frame *B* are suitable vertical guides, such as *11* and *12*, (Figs. 8 and 7) for the stack of sheets and the top sheet of the stack is maintained at a predetermined level, such as that shown in Fig. 8, by means which cause the platform *10* to be moved step by step upwardly at each operation of the press. Such means include two elevator drums *13*, one on each side of frame *B*, which drums are fixed to a shaft *14*, rotatably mounted in the frame. An eye *16* is fixed to each drum and a cable *17* is looped through each eye,—its two extensions passing upwardly over a sheave or sheaves *18*, and thence downwardly for connection in laterally spaced relation to platform *10*.

The elevator drums *13* are operated by the following mechanism. Fixed to shaft *14* is a gear *19*, driven by a pinion *20*, which is mounted on a stud *21*, fixed to frame *B*. Fixed to pinion *20* is a gear *22*, driven by a pinion *23* to which is fixed a ratchet wheel *24*, the latter and pinion *23* being rotatable on a stud *25* fixed to frame *B*. A holding pawl *26*, mounted on frame *B* is associated with ratchet wheel *24* as is also an actuating pawl *27*, carried by an arm *28*, pivotally mounted on stud *25*. Arm *28* is connected by a link *29* to a lever *30*, which is pivotally mounted intermediate its ends on frame *B* and the connection of the link to the lever is preferably adjustable, as indicated, to enable the throw of pawl *27* to be varied, as desired. Lever *30* is connected by a link *31* to one of two similar levers *32*, which are mounted intermediate their ends on a cross shaft *33* (rotatably mounted in frame *B*) and disposed one at each end of the shaft. The lower ends of levers *32* are connected by a link *34* to the described crank pins *d*, whereby on each swinging movement of platen *c*, the platform *10* will be elevated one step,—the arrangement being such that the top sheet of the stack of sheets on the platform is maintained at a constant level.

The sheet feeding mechanism, whereby the uppermost sheet of the stack is removed therefrom and transferred to the platen *c*, consists of two distinct mechanisms, both of which are operated from the lever *32*. One of these mechanisms functions to separate the top sheet of the stack and push it forwardly into position to be taken by the other, or transferring mechanism, and car-

ried to the platen. The transferring mechanism includes nippers which grasp the sheet *s*, when positioned as described, and pulls it by its forward edge over the platen. The nippers reciprocate in guides and the guides are pivoted to swing in timed relation with the reciprocating movement of the nippers so that the latter carries not only the sheet forwardly but downwardly as well. By this arrangement the nippers, when they release the sheet, are so close to the platen that there is, as a practical matter, no chance for the sheet to become improperly positioned as it falls to the platen.

The sheet separating and positioning mechanism will first be described with particular reference to Figs. 3, 4 and 5. This mechanism functions to push the top sheet *s* forwardly from the position shown by full lines to that shown by dotted lines in Fig. 8 and over the upper face of an angle iron *35*. Referring to Fig. 3, two shafts *36* and *37*, one vertically above the other, extend transversely across the magazine, well above the level of the uppermost sheet *s* therein, and are supported near their ends by brackets *38* secured to the upper faces of the top side bars of frame *B*. The lower shaft *37* is oscillated back and forth from one of the levers *32* and for this purpose has fixed to its forward end, outside bracket *38*, a depending arm *39* which is connected by a link *40* to the lever *32* at the same point at which the described link *31* is connected. Fixed to shaft *37* in laterally spaced relation and between the brackets *38* are two depending arms *41*, the lower ends of which are pivotally connected to the rear ends of arms *42* which carry suitable sheet pushers *43*, herein shown as small sections of hacksaw blades. These pushers are moved back and forth over the stack of sheets but are held elevated above the uppermost sheet during their rearward stroke and allowed to engage the uppermost sheet during their forward stroke, whereby the uppermost sheet *s* may be moved as above described.

The shaft *36* controls the raising and lowering of the sheet pushers *43* and to this end has fixed thereto two forwardly extending arms *44*, one overlying each arm *42* and connected therewith by a suspension link *45*. The lower pivot pin *46* of link *45* rides in a long slot *47* provided in arm *42*, whereby the latter is free for its reciprocating movement. The suspension link is restrained from swinging back and forth by a radius rod *48*. As shown the latter is made of a wire, one end of which is coiled around shaft *37* and the other end of which is bent at right angles and passed through a hole in link *45*. On the rear end of shaft *36* and outside the adjacent bearing *38* is a collar *49* (Fig. 4) having a notch *50*

adapted to receive the inner end of a latch 51 pivoted at 52 to the adjacent bracket 38, whereby shaft 36 and thus the pushers 43 are held in the elevated positions illustrated. On collar 49 is fixed an arm 52' which is connected by a spring 53 to a pin 54 on latch 51, whereby the latch is urged toward collar 49 and whereby the latter and shaft 36 can be turned downwardly when latch 51 is withdrawn from notch 50.

The raising and lowering of the pushers 43 is controlled from the shaft 37 which reciprocates them. For lowering the pushers, a cam 55 is fixed to shaft 37 and located below collar 49 and in the path of latch 51. Cam 55 is arranged to engage latch 51 at the end of the rearward stroke of pushers 43 and to move the latch out of notch 50, whereby shaft 36 is turned by spring 53 and the pushers 43 forced into engagement with the uppermost sheet *s* of the stack. The pushers then move forwardly to advance the top sheet *s*, as described, and, as they are thus moved, a finger 56, fixed to shaft 37, swings upwardly and approaches a set screw 57 threaded in a collar 58 fixed on shaft 36. At or near the end of the forward movement of the pushers, finger 56 engages and moves the set screw 57 and causes shaft 36 to turn in a clockwise direction sufficiently to enable latch 51 to be drawn into place in notch 50, whereby the pushers are held elevated during their rearward strokes.

At the rear of the magazine (Fig. 7), is a knife 59, adjustably mounted in a bracket 60, which in turn is adjustably mounted on a bar 61, extending centrally and longitudinally of the magazine from its rear edge to a position substantially midway between the front and rear edges of the magazine. Bar 61 is spaced above the uppermost sheet *s* of the stack and is supported at one end from the rear cross member of frame B (Fig. 7) and at the other end by a cross member 62, (Figs. 6 and 8) which is connected at its ends to the side members of frame B. The knife is arranged to penetrate through several of the uppermost sheets of the stack and to thereby hold the underlying sheets from being carried forwardly with the uppermost sheet by frictional engagement. The uppermost sheet, when moved forwardly by the pushers 43, is ripped away from the knife but the mutilation of the sheet, thus caused, occurs in the margin which is later trimmed off.

The sheet removing means, whereby a sheet positioned by the pushers 43 is carried to the platen of the press, include two or more nippers which are moved to and fro by the levers 32, heretofore described. A shaft 63 extends between and connects the two levers 32 and is fixed at its ends to the latter. Intermediate the levers 32 are located nipper arms 64, which are mounted

at one end on shaft 63 and are free to turn thereon. The other ends of the arms 64 are connected by a shaft 65 and are free to turn thereon. The ends of shaft 65 are connected to the forward ends of two slide bars 66, which are disposed one on each side of frame B. Each bar 66 is slidably mounted in ways formed in a guide piece 67 which is pivoted to frame B at 68. Gibs 69 (Fig. 8) serve to hold bar 66 in place in the guide piece 67. Each guide piece 67 is arranged to be swung on its pivot 68 by means of a slide 70 which is pivotally connected at its upper end by a pin and slot connection 71 to the side piece and is suitably mounted to slide vertically on frame B. Each lever 32 carries a path cam 72 with which a roll 73 on the lower end and on the outer face of the slide 70 is engaged. As the levers 32 start to swing counter-clockwise from the position illustrated in Fig. 3, the nipper arms 64 push on shaft 65 and cause bars 66 to be drawn forwardly in their guide pieces 67. The cams 72 do not at first lift the guide pieces 67 so that the shaft 65 travels horizontally outward. Eventually, however, cams 72 cause the guide pieces 67 to be swung upwardly while the bars 66 continue to be drawn out further in guide pieces, with the result that the shaft 65 begins to travel downwardly as well as forwardly. Finally, the shaft 65 assumes a position, such as is shown in Fig. 2, wherein it lies fairly close to the receiving face of platen *c* and near its inner edge, the bars 66 becoming approximately parallel to the bed of the platen.

The nippers are carried by shaft 65 whereby the leading edge of a sheet *s* is pulled along in the path described until it comes into a position such that it can safely be released with assurance that it will drop into proper position on the platen. Each nipper comprises a fixed jaw 74 formed as a part of the nipper arm 64 at a location close to shaft 65. The movable jaw 75 underlies jaw 74 and is an offset part of a lever 76 pivoted on shaft 65 adjacent arm 64. A spring 77 connects a pin 78 on the upper end of lever 76 to bar 64 and extends to hold jaw 75 in the open position illustrated in Fig. 8. The upper end of lever 76 is also connected by a link 79 to the free end of a lever 80 mounted on shaft 63 and free to turn thereon. Pin 78 projects beyond both sides of lever 76 and, on one side, overlies arm 64 and is adapted to engage therewith in a notch 81 to limit the degree of opening movement of the nipper jaw 75. When jaw 75 is closed, a pin 82 on lever 80 engages arm 64 and prevents further movement thereof in a clockwise direction and, when lever 80 is thus positioned, the point of pivotal connection between link 79 and lever 80 crosses the line connecting the centers of pin 78 and shaft 63.

63 whereby the pull of spring 77 is ineffective to open the jaw 75 and the jaws are locked closed.

The jaw 75 is open as shown in Fig. 8, as 5 it moves to the right and approaches the forward edge of sheet *s*. As arms 32 near the end of their movement in the described direction, the ends of levers 80 are carried into engagement with set screws 84, adjustably mounted in upstanding relation on the cross bar 62, heretofore described. The arrangement is such that arms 80 are moved far enough to close jaws 75 and they are thereafter held closed by the toggle link 10 arrangement above described. Adjacent each nipper bar 64 and fixed to shaft 63 is an arm 85 carrying an adjustable abutment, in the nature of a set screw 86, which lies in the path of the rear end of a link 79. As 15 the arms 32 swing to the left, as viewed in Fig. 8, the nipper arms naturally turn on shaft 63 and the angle between link 79 and set screw 86 decreases until the two finally engage at or near the end of the outward 20 stroke of arms 32, whereby link 79 is pushed downwardly far enough to allow spring 77 to open jaw 75 and release sheet *s*.

In operation, the platen *c* oscillates continuously, thereby moving the levers 32 in a 25 similar fashion. The sheet separating means operates to position a sheet for the nipper mechanism during the closing movement of the platen and during the same movement of the platen the nipper mechanism returns 30 toward the magazine with jaws 75 in open position, as shown in Fig. 8. As the nipper mechanism nears the end of its stroke, the uppermost sheet *s* of the stack is pushed out by the sheet separating mechanism into the 35 position shown by dotted lines in Fig. 8. The nippers approach the sheet and jaws 75 are closed thereupon by reason of the abutment of stop 86 with the crank arm 80. The latter is moved, as described, to lock jaws 75 40 by a toggle action in closed position. This action occurs as the platen *c* moves into engagement with bed *b*. As the platen moves away from its bed, the levers 32 push the nipper links or frames 64 toward the platen, and the leading ends of such links, being 45 connected to the slides 66 travel at first in a straight line parallel with the top face of the stack of sheets in the magazine. Eventually, however, cam 72 comes into play and lifts 50 the slides into inclined relation with said face and finally into positions more nearly parallel with the sheet receiving face of platen *c*, when it is fully open and in sheet receiving position. This causes the nippers 55 to dip downwardly and travel in a curved path until they finally approach very closely to the lowest edge of the platen. At such time, the stop 86 on arm 85 engages the crank arm 80 and breaks the toggle which holds jaw 75 closed. The spring 77 then

snaps jaw 75 open to release the sheet, which has to drop only a very short distance and can therefore, be positioned properly on the platen against stop *v* with reasonable certainty.

The sheet, carried by the platen *c* against bed *b*, is removed by any suitable nipper mechanism, represented generally by reference letter *w*. Inasmuch as the present invention, relates entirely to the feeding of 75 the sheet, it has not been considered necessary to describe in detail the means for removing the sheets from the platen.

The invention has been disclosed herein, in an embodiment at present preferred, for 80 illustrative purposes but the scope of the invention is defined by the appended claims rather than by the foregoing description.

What I claim is:—

1. The combination with a press having a 85 swinging platen opening to a sheet receiving position in which the platen is inclined to the horizontal and slopes downwardly toward its bed, of a magazine adjacent thereto for holding a vertical stack of sheets to 90 be fed to the platen, a lever pivotally mounted on said magazine and connected to the platen to continuously oscillate therewith, a slideway pivoted to the magazine and movable from a position substantially 95 parallel to the top face of said stack to a position substantially parallel to the face of said platen, connections between said slideway and lever to move the former intermittently from the latter, a slide mounted in 100 said slideway, a link connecting said lever to the forward end of said slide, and a fixed and a movable nipper jaw carried by said link.

2. The combination with a press having a 105 swinging platen opening to a sheet receiving position in which the platen is inclined to the horizontal and slopes downwardly toward its bed, of a magazine adjacent thereto for holding a vertical stack of sheets 110 to be fed to the platen, a pair of levers pivotally mounted on said magazine one on each side thereof, and connected to the platen to oscillate therewith, a cross bar connecting the upper ends of said levers and fixed thereto, a pair of slideways pivoted to 115 said magazine one on each side thereof and connected to the adjacent lever to be moved thereby during part of the oscillatory movement of the levers, a slide mounted to reciprocate in each slideway, a cross bar connecting the leading ends of the slides, a link connecting both said cross bars and free to turn on the former, a nipper jaw pivotally mounted on the last named cross bar and 120 cooperating with an adjacent portion of said link to grip or release a sheet placed therebetween, a crank arm mounted to turn on the first named cross bar, a link connecting 125 said crank arm and nipper jaw, said 130

arm and link forming a toggle to hold the latter in closed position, an arm fixed on the first named cross bar and operable at the end of the oscillation of said levers in one direction to break the toggle and open the nipper jaw, a spring to hold said jaw in open position, and a fixed abutment engage-

able with said crank arm at the end of the oscillation of said levers in the other direction to move it and cause the closing of said nipper jaw. 10

In testimony whereof I have affixed my signature.

CARL F. FRAUENBERGER.
